AIR VALVE

Joseph F. Stanwich, Chicago, Ill., assignor to
 The Dole Valve Company, Chicago, Ill., a corporation of Illinois

Application June 7, 1935, Serial No. 25,358

7 Claims. (Cl. 137—122)

This invention relates to air valves and has for an object to provide a new and improved device of this description.

The invention has a further object to provide an air valve which will be simple in construction and which can be manufactured at a low cost.

The invention has as a further object to provide an air valve with a water discharge pipe which can be placed in position after the air valve proper is finished.

The invention has other objects which will be more particularly pointed out in the accompanying description.

Referring now to the drawing, Fig. 1 is a view showing one form of the air valve embodying the invention;

Fig. 2 is a vertical sectional view taken through Fig. 1, with the parts in position;

Fig. 3 is a side elevation of the bottom of the air valve before the water discharge pipe is placed in position;

Fig. 4 is a view of the outer casing of the valve, separate from the bottom;

Fig. 5 is a side elevation of the water discharge pipe;

Fig. 6 is a plan view of the bottom of the air valve, with the water discharge pipe therein and before the end of the water discharge pipe is flared;

Fig. 7 is a view similar to Fig. 6 after the end of the water discharge pipe has been flared;

Fig. 8 is a view of the bottom of the air valve, showing a modified construction;

Fig. 9 is a plan view of the bottom of the air valve shown in Fig. 8, with the water discharge pipe in position after its end is flared;

Fig. 10 is a view of the end of the water discharge pipe before its end is flared and showing a slot therein;

Fig. 11 is a view showing a further modified construction; and

Fig. 12 is a view showing a further modified construction.

Like numerals refer to like parts throughout the several figures.

In the manufacture of the air valve at present all the parts are first assembled, including the bottom and the water discharge pipe, and the bottom projects down below the lower end of the casing. The valve when thus assembled is plated, is then put upon the test rack and tested for air, and is then tested for steam. The valve is then buffeted and polished. During all these operations the water discharge pipe is in position and in the way and makes the several operations quite

difficult. In the present construction these difficulties are eliminated as the water discharge pipe is not attached until all the steps have been taken and the air valve itself has been completed.

Referring now to the drawing, there is illustrated an air valve having a casing 1 and a bottom 2. The casing 1 is made of comparatively thin sheet material which can be plated and burnished. The bottom 2 is preferably cast of any suitable cast metal. The casing is provided with an opening 3 near the bottom and the bottom 2 is provided with an upstanding wall portion 4, to which is connected a hollow screw threaded nipple 5, by means of which the air valve is attached to the radiator or other device in connection with which it is used. The bottom is provided with an upstanding member 6 upon which rests the hollow receptacle 7, which acts as a float and which also preferably contains an expansible fluid, which when steam enters the casing 1 becomes heated and expands and forces the bottom of the float outwardly so as to raise it up and cause the valve member 8 thereon to engage its seat 9 and close the escape passage-way 10 leading from the casing 1 to the outside atmosphere.

In the manufacture of the valve the casing and the bottom are fastened together before the water discharge pipe is placed in position, the bottom and the casing being connected together by solder or other means, the lower end of the casing surrounding the bottom and its lower edge being preferably flush with the lower face of the bottom, so that the bottom does not show and need not be finished, but can consist simply of the rough casting.

Some means is provided for attaching the water discharge pipe 11 which discharges water from the casing, so as to prevent such water from returning therein. In the present device there is provided means for flaring or enlarging the inner end of the water discharge pipe as it is pushed through the hollow nipple 5. For this purpose, there is provided on the inside of the air valve a flaring device arranged so that when the water discharge pipe is forced against it, the end of the water discharge pipe is flared or enlarged, so that it will remain attached to the valve and will not be disconnected therefrom throughout the ordinary use of the valve. There is illustrated in Figs. 3 and 6 a particular form of device for flaring the end of the water discharge pipe which consists in providing the upstanding member 6 with a flaring part 12. The end of the water discharge pipe 11 is forced

against this flaring part and is flared or enlarged so that it spreads out and is of greater size than the diameter of the hole through the nipple 5, and will thus be retained in position. 5 Any suitable construction for securing the flaring of the end of the water discharge pipe 11 may be utilized. There is illustrated in the drawing one construction wherein the flaring part 12 has a conical shape. The end of the water discharge pipe is then pushed against this conical flaring member 12 and rotated. The flaring member at its base is larger than the pipe so that it expands or flares the end of the pipe, as shown in Fig. 7, thus making it larger than the 15 opening in the nipple 5 so that the pipe cannot be readily withdrawn, but will remain in position during the handling and use of the air valve.

In Figs. 8 and 9 there is illustrated a modified 20 construction wherein instead of having a conical shaped flaring member 12, the flaring member 12a is wedge shaped. With this construction I prefer to provide the end of the water discharge pipe with a slot 13, so that when it is pushed in 25 against the wedge-shaped flaring member the end of the pipe will be flared or enlarged, as shown in Fig. 9, so that the pipe cannot be easily withdrawn from the valve. The slot 13 may be used with the conical shaped flaring member if desired.

In the making of the device, the parts are all connected together except the water discharge pipe. The bottom and the casing are preferably soldered. The nipple 5 is also soldered around 35 the hole 3 so as to prevent any leak. The valve thus assembled without the water discharge pipe then goes through the several operations of buffing, polishing, plating, testing and color buffing, and when completed, the water discharge pipe 40 11 is pushed into the nipple 5 and its end is flared by the flaring element, and the valve thus made ready for use.

It will further be seen that in this construction, there is no separate support for the hollow receptacle or float 7, but that this support is integral with the bottom of the valve and that it acts not only as a support, but as the flaring device for the end of the water discharge pipe. I have shown the unstanding part 6 as integral 50 with the bottom and the flaring member 12 as integral with the upstanding member, but it is of course evident that they may be separate and attached if desired.

In Figs. 11 and 12 I have shown modified constructions wherein the tube 11 is cut away at 13 having a portion of the metal removed. This metal may be cut away at two opposite points. The ends 14 are bent over. After the valve is 60 finished the slotted end of the tube with bent ends 14 is pushed in nipple 5, the tube being of material sufficiently elastic to permit portions of the tube to bend inwardly towards each other to permit the end being inserted in the nipple, and when the projections 14 pass beyond the 65 nipple they will move outwardly so as to engage the wall of the nipple, thus holding the tube in place. These ends may simply engage the walls surrounding the hole of the nipple, as shown in Fig. 12, or the nipple may be formed with a flaring member 15 on it, as shown in Fig. 11, so that after the tube is inserted the ends 14 move out due to their elasticity, and the tube can then be rotated so as to bring the faces of the 70 75 projections 14 in contact with flaring member

15, which tends to flare them out and properly shape them.

I have shown a particular construction in the drawing, but it is of course evident that parts may be varied in many particulars without departing from the spirit of the invention as set out in the claims hereto appended, and I therefore do not limit myself to the particular construction shown.

I claim:

1. An air valve comprising a casing, a valve element in said casing, said casing having a passageway communicating with the outside atmosphere, a bottom for said casing, an upstanding support on said bottom for supporting said valve element in proximity to said passageway, said casing being provided with an opening, a water discharge pipe projecting from the casing through said opening, and a flaring device on the interior of the casing and forming a part of said support for the valve element and opposite said opening, whereby the pipe can be brought into contact with said flaring device to flare the end of the pipe so that it will remain in position in the casing.

2. An air valve comprising a casing, a valve element in said casing, said casing having a passageway communicating with the outside atmosphere, a bottom for said casing, an upstanding support on said bottom for supporting said valve element in proximity to said passageway, said casing being provided with an opening, a water discharge pipe projecting from the casing through said opening, and a flaring device on the interior of the casing and forming a part of said support for the valve element and opposite said opening, so that the pipe can be brought into contact with said flaring device to flare the end of the pipe so that it will remain in position in the casing, the end of the water discharge pipe which is to be flared being weakened to assist the flaring operation.

3. An air valve comprising a casing, a valve element in said casing, said casing having a passageway communicating with the outside atmosphere, a bottom for said casing, an upstanding support on said bottom for supporting said valve element in proximity to said passageway, said casing being provided with an opening, a water discharge pipe projecting from the casing through said opening, and a flaring device on the interior of the casing and forming a part of said support for the valve element and opposite said opening, so that the pipe can be brought into contact with said flaring device to flare the end of the pipe so that it will remain in position in the casing, the end of the water discharge pipe being slotted for a portion of its length, to assist in the flaring of its end.

4. An air valve comprising an integral casing of thin material, a valve element in said casing, a bottom for the casing having a laterally projecting nipple thereon, the casing having an opening near the bottom, through which the nipple is received when the bottom is placed in position.

5. An air valve comprising an integral casing of thin material, a valve element in said casing, a bottom for the casing having a laterally projecting nipple thereon, the casing having an opening near the bottom, through which the nipple is received when the bottom is placed in position, the lower face of the bottom being substantially in the same plane as the lower edge of the casing.

6. An air valve comprising an integral casing of thin material, a valve element in said casing, a bottom for the casing having a laterally projecting nipple thereon, the casing having an opening near the bottom, through which the nipple is received when the bottom is placed in position, a water discharge pipe adapted to be inserted through said nipple after the other parts are assembled, and means inside the casing rendering it non-removable.

7. An air valve comprising a casing, a bottom therefor, a nipple connected with the bottom, for attaching the air valve to a radiator, a valve element in the casing, a water discharge pipe extending through said nipple, a flaring device 5 within the casing, integral with the bottom, for flaring the end of said water discharge pipe, so as to retain it attached to the casing, the flaring device acting as a support for the valve element.

JOSEPH F. STANWICH. 10
